[57] CLAIM

The ornamental design for a silo playground climber and slide, substantially as shown and described.

DESCRIPTION

FIG. 1 is a right side elevational view of a silo playground climber showing my new design, the left side being a mirror image thereof;

FIG. 2 is a front elevational view;

FIG. 3 is a rear elevational view of my new design, and

FIG. 4 is a top plan view.

FIG. 2

FIG. 1

FIG. 3.

FIG. 4.
